UNITED STATES PATENT OFFICE

2,418,670

COPYHOLDER

Alvin E. Schubert and John C. Haelen, Rochester, N. Y., assignors to Eastman Kodak Company, Rochester, N. Y., a corporation of New Jersey

Application February 3, 1944, Serial No. 520,892

10 Claims. (Cl. 45—86)

1

The present invention relates to a copyholder and more particularly to a copyholder having a pair of copy supports which are relatively movable with respect to each other and/or with respect to a platen member.

While copyholders of the same general type are known, such prior art copyholders either can not be readily adjusted with respect to a platen member or are spring pressed against the platen member so as to require locking or blocking before opening of the platen member so that the copy and copy supports will not be sprung upwardly. Also, known copyholders may change the relative positions of the copy supports when the platen member is opened.

The primary object of the present invention is the provision of a copyholder in which the copy supports are mounted upon a linkage in turn supported by a means for raising or lowering the linkage and copy supports and for restraining relative movement of the copy supports.

A further object of the invention is the provision of a copyholder comprising a casing provided with guideways, a copy receiving assembly including a linkage mounted for movement in said guideways and a rope means frictionally engaging said linkage and supporting the copy receiving assembly at various positions within the casing.

Still another object of the invention is the provision of a copy receiving assembly movable mounted by a rope means which may be adjusted for supporting the assembly in various positions to press a book or other copy against a platen member without springing the book or copy upwardly when the platen member is opened.

Other and further objects of the invention will be evident to those skilled in the art from the following description.

The aforementioned and other objects of the invention are embodied in a copyholder comprising a casing having a pair of spaced parallel walls each provided with oppositely located guideways, a pair of copy supports, one or more parallelogram linkages for supporting said copy supports, a pair of transverse rods having their ends in engagement with said guideways and extending through corresponding links of the parallelogram linkages, a pair of pulleys mounted on one of said rods and attached to links of the parallelogram linkages, lengths of rope attached at opposite ends to the casing and intermediately encircling respective pulleys, and an adjustable means connected to and for varying the position of said lengths of rope to change the positions

of the copy supports with respect to the casing.

The illustrated embodiment of the invention shows a platen member mounted upon the casing and against which the copy or book is pressed by the copy supports. However, the copy receiving assembly and rope means according to the invention may be used in copyholders without such a platen member.

Reference is hereby made to the accompanying drawings wherein similar reference characters designate similar elements and wherein:

Fig. 1 is a plan view of the copyholder according to the invention.

Fig. 2 is a vertical longitudinal section through the copyholder of the invention.

Fig. 3 is a fragmentary elevation of the adjusting means as viewed from the line 3—3 of Fig. 2.

Fig. 4 is a vertical longitudinal section similar to Fig. 2 but showing the copy receiving assembly in a lowered position.

Fig. 5 is a vertical transverse section through the copyholder taken on the line 5—5 of Fig. 2.

Fig. 6 is a fragmentary vertical section showing the latch for the platen member; and

Fig. 7 is a fragmentary perspective of the copy attaching means for holding the copy upon the copy supports.

In the illustrated embodiment the copyholder of the invention comprises generally a casing, a copy receiving assembly, a rope means, and an adjustable means. The copy receiving assembly includes a pair of copy supports which are shown as mounted upon a pair of parallelogram linkages. However, it is to be understood that said copy supports may be mounted upon a single linkage within the scope of the invention. The term "rope means" as used herein includes any elongated material such as cable, cord, wire, etc. and which has some stretch or slight resiliency for a purpose to be explained. Also, the invention is equally applicable to a copyholder with or without a platen member.

The casing for the copyholder has a front wall 10, a back wall 11, and side walls 12. Bottom walls 33 having feet 34 may be fastened to the lower edges of said walls 10, 11 and 12. The front and back walls 10 and 11 are each provided with oppositely located vertical guideways 13 which are preferably formed each by a pair of angle irons 14. Handles 15 may be attached to each of the side walls 12.

The platen member comprises a frame 16 and preferably includes a transparent member 17 conveniently made of glass and held in place by re-

ainers 18 and screws 19, see Fig. 5. Said platen member is removably or hingedly mounted upon the casing in any suitable manner such as that indicated in the drawings by way of illustration. Upright supports 20 are fastened by bolts 21 to the casing or side walls 12. A U-shaped frame extends around three sides of platen frame 16 and includes side members 22 pivotally connected by bolts 23 to said supports 20 and has a front member 24, see Figs. 5 and 6, carrying a handle 25 and spring latch 26 for engaging the catch 27 mounted on front wall 10. The platen member has angle plates 28 centrally mounted at each end of plate frame 16 and connected to the side members 22 of the U-shaped frame by means of bolts 29. Said side members 22 extend beyond said back wall 11 and coil springs 30 are attached at one end to eyelets 31 on said extensions of side members 22 and at the other end to eyelets 32 on the back wall 11. As a result, the platen member is normally held by the coil springs 30 in a raised position as indicated by the dotted lines in Fig. 5. The platen member may be lowered by pressing on the handle 25 and moving spring latch 26 into engagement with catch 27, the platen frame 16 being rotatably mounted upon the U-shaped frame so that the platen member and/or transparent member thereof may locate itself upon the top edges of the casing walls or against the copy on the receiving assembly.

The copy receiving assembly comprises generally a pair of copy supports and one or more linkages operatively connected to said supports and permitting relative movement thereof. The copy supports 35 and 36 are preferably covered with a rubber mat 37 also extending over the spacing between the supports 35 and 36 and for supporting the back of a book to be copied. Such a book 38 may have covers 39 and 40, although the copyholder is not limited to use with any particular form of copy such as a bound volume. The linkage for the copy supports is preferably a parallelogram linkage. Specifically, a cross bar 41 has depending ends 42 and 43 and a cross bar 44 has depending ends such as 45. Straps 46 each have curved ends 47 provided with slots 48 for engaging headed screws 49 on each of the cross bars 41 and 44. As best shown in Fig. 2, said straps 46 may extend over the book covers 39 and 40 to hold them on the respective copy supports 35 and 36. Two pairs of links 50 and 51, 52 and 53 are pivotally connected at opposite ends to the depending ends of the cross bars 41 and 44. Link 50 is pivotally connected at one end to depending end 42 of cross bar 41 by a bolt 54 and at the other end to the depending end 45 of cross bar 44 by a bolt 55. Link 51 is pivotally connected at one end to depending end 42 by a bolt 56 and at the other end to depending end 45 by bolt 57, links 52 and 53 being pivotally connected in a similar manner to the opposite depending ends of said cross bars 41 and 44. Since the pivotal connections of the links to the depending ends of the cross bars 41 and 44 are vertically spaced, a parallelogram linkage is formed for supporting the copy supports 35 and 36. Preferably as shown, there is such a parallelogram linkage adjacent each of front wall 10 and back wall 11 for a stronger arrangement of the copy receiving assembly.

A transverse rod 58 extends through the centers of links 50 and 52 and carries on each end a roller 59 for rolling engagement with the angle irons 14 forming the guideways in the walls 10 and 11. A second transverse rod 60 also has roll-

ers 61 on each end thereof for engaging the angle irons 14 of the guide-ways 13 and extends through the centers of links 51 and 53. When the copy receiving assembly is supported by said rods 58 and 60, the copy supports 35 and 36 are maintained in parallel relation to each other during their relative movement and so that the copy thereon or rubber mat 37 is supported in a substantially horizontal plane.

10 A pulley 62 is fastened to link 51 and a pulley 63 is fastened to link 53 by a pair of screws 64, see Figs. 2 and 4. The transverse rod 60 is free to rotate within said links 51 and 53 and within said pulleys 62 and 63. The peripheries of said pulleys 62 and 63 are recessed in a known manner to receive one or more turns of a rope member next to be described.

In the illustrated embodiment the rope member 65 is fastened at one end in the recessed periphery of a pulley 66 mounted upon a rod 67 journaled at each end in the walls 10 and 11. Said rope member 65 extends from said pulley 66, is wrapped at least once around the periphery of pulley 63, then extends to the left-hand side wall 12, being fastened thereto by clamps 68 whereupon said rope member 65 encircles pulley 62 and extends to and is fastened to a pulley 69 upon the other end of rod 67 adjacent the front wall 10. The arrangement of said rope member 65 is best illustrated in Fig. 1 and it is obvious that rotation of rod 67 will raise or lower the copy receiving assembly comprising the transverse rods 58 and 60, the parallelogram linkages and the copy supports 35 and 36. For instance, said rope member 65 may support the copy receiving assembly in the position shown in full lines in Fig. 4 for supporting a relatively thick book or volume between copy supports 35 and 36 and the platen member. Winding of the rope member onto pulleys 66 and 69 will shorten the stretches between pulley 66 and clamp 68 and between pulley 69 and the other clamp 68 so that the copy receiving assembly will be elevated to a position such as shown in Fig. 2 for holding an average book against the transparent member 17 of the platen means. Finally, the copy receiving assembly may be elevated as shown in dotted lines in Fig. 4 for holding a single sheet or document in contact with the transparent member 17.

50 An adjustable means is provided for manual rotation of said rod 67 and is preferably non-reversible as shown. A bracket 70 is fastened to one of side walls 12 by machine screws 71 and a shaft 72 is journaled in said bracket and 55 extends through side wall 12 to receive a knob 73. A worm 74 is mounted upon said shaft 72 between the side walls of bracket 70 and meshes with a worm wheel 75 which is fastened to rod 67 by a set screw 76. As a result, rotation of knob 73 will cause rotation of the rod 67 in a corresponding direction so that the pulleys 66 and 69 are rotated either to wind or unwind the rope member 65. The worm 74 and worm wheel 75 are arranged in a well known manner 60 so that the coefficient of friction therebetween is greater than the tangent of the helix angle of the worm and knob 73 can not be rotated by any force exerted upon the rod 67. In other words, the knob 73 may be turned to adjust the copy receiving assembly to any position and weight or pressure upon the copy supports 35 and 36 will not alter the setting of rod 67 by knob 73.

The outstanding advantage of the use of one or more rope members to support the copy re-

ceiving assembly according to the invention is that said rope member may be shortened or lengthened to vary the position of the assembly and frictionally engages the pulleys 62 and 63 which are attached to the parallelogram linkages so that the copy supports 35 and 36 are frictionally held in such position. In other words, when the platen member is open the copy receiving assembly remains substantially in the same position and the copy supports 35 and 36 do not move relatively to each other even though there may be considerably more than half of the weight of the copy or book upon one of said supports. Thus, if the top pages of a bound volume are in the same plane by reason of the copy receiving assembly having been pressed against the platen member when closed, the top pages of the book or volume will remain in the same position even after the platen member is opened and even if the weight of the book being copied is quite unevenly divided between the supports 35 and 36. The slight inherent resiliency in the material of the rope member 65 permits the elimination of all springs from the copyholder.

In practice, the bound volume may have its covers attached to copy supports 35 and 36 by straps 46, the platen member is closed against the action of coil springs 30 and held in such closed position by the spring latch 26 engaging the catch 27. Knob 13 is then rotated to raise the entire copy receiving assembly until the open pages of the book are pressed against the glass platen. The platen member may be opened and the pages of the book turned to another place and closing of the platen member will press on the top pages of the book halves to readjust the relative positions of the copy supports 35 and 36. Such readjustment is permitted by the frictional engagement between the rope member 65 and the pulleys 62 and 63. Also, the copy receiving assembly may be elevated so as to press a single sheet or document against the transparent member 17 of the platen member and the copy supports 35 and 36 will be moved into the same plane and held in that position by the frictional engagement between the rope member 65 and the pulleys 62 and 63.

Consequently, the frictional engagement between the supporting rope member and said pulleys 62 and 63 either holds the platen members 35 and 36 in any set position or permits their readjustment by reason of different thicknesses of copy between the respective copy supports 35 and 36 and the platen member. Furthermore, said rope member provides a very simple and effective manner of adjusting the spacing between said copy supports 35 and 36 and the transparent member 17 of the platen member so that different thicknesses of copy may be held flat against said transparent member 17.

As indicated herein, the copyholder according to the invention may be varied, such as by providing a single parallelogram linkage to support the copy supports 35 and 36. Other modifications of the invention are also possible so that the present disclosure is to be construed in an illustrative sense, the scope of the invention being defined by the claims which follow.

Having now particularly described our invention, what we desire to secure by Letters Patent of the United States and what we claim is:

1. A copy holder comprising a casing providing a pair of opposed guideways, a platen member mounted on the top of said casing, a copy re-

ceiving assembly including a pair of copy supports, a supporting linkage operatively connected to said copy supports and a pair of rotatable members each attached to said linkage, a mounting means between said guideways and said supporting linkage and for guiding said copy receiving assembly within said casing, and a rope means connected to said casing at opposite points higher than the bottoms of said rotatable members and frictionally engaging said rotatable members, supporting said copy receiving assembly within said casing and frictionally restraining movement of said linkage and relative movement of said supports.

2. A copy holder comprising a casing providing a pair of opposed guideways, a platen member mounted on the top of said casing, a copy receiving assembly including a pair of copy supports, a supporting linkage operatively connected to said supports and a pair of rotatable members each attached to said linkage, a mounting means between said guideways and said supporting linkage and for guiding said copy receiving assembly within said casing, a rope member connected to said casing at opposite points higher than the bottoms of said rotatable members frictionally engaging said rotatable members, supporting said copy receiving assembly and frictionally restraining movement of said linkage and relative movement of said copy supports, and an adjustable means connected to and for varying the position of said rope member to change the position of said assembly with respect to said casing.

3. A copy holder comprising a casing providing a pair of opposed guideways, a platen member mounted on the top of said casing, a copy receiving assembly including a pair of copy supports, a supporting linkage operatively connected to said copy supports and a pair of rotatable members each attached to said linkage, a mounting means between said guideways and said supporting linkage and for guiding said copy receiving assembly within said casing, a rope member connected to said casing at opposite points higher than the bottoms of said rotatable members frictionally engaging said rotatable members, supporting said copy receiving assembly and frictionally restraining movement of said linkage and relative movement of said copy supports, and an adjustable means including a second rotatable member for winding or unwinding said rope member and a non-reversible driving connection operatively connected to said second rotatable member, manually operable for winding or unwinding said rope member but not operable by tension on said rope member.

4. A copy holder comprising a casing providing a pair of opposed guideways, a platen member mounted on the top of said casing, a parallelogram linkage having two pairs of opposite links, a pair of copy supports mounted respectively on each link of one pair of opposite links thereof, a pair of rods each having their opposite ends slideable in said guideways and respectively extending through and supporting the links of the other pair of opposite links, a pair of pulleys adjacent opposite ends of one of said rods and attached to one of said links of said other pair, and a rope member supported at each end by the upper part of said casing and intermediately encircling said pulleys to restrain movement of said linkage and relative movement of said copy supports.

5. A copy holder comprising a casing providing a pair of opposed guideways, a platen member on said casing, a copy receiving assembly including

a pair of copy supports, a supporting linkage operatively connected to said copy supports and a pair of rotatable members located at each side of said copy supports and connected to said linkage, a mounting means between said guideways and said supporting linkage and for guiding said copy receiving assembly within said casing, a rope means connected at opposite points to the upper portion of said casing and frictionally engaging said rotatable members and for supporting said copy receiving assembly within said casing, and an adjustable means connected to and varying the position of said rope member to move copy on said copy supports into engagement with said platen member.

6. A copy holder comprising a casing providing a pair of opposed guideways, a platen member mounted on said casing for movement to closed and open positions, a copy receiving assembly including a pair of copy supports, a supporting linkage operatively connected to said copy supports and a pair of rotatable members located at each side of said copy supports and connected to said linkage, a mounting means between said guideways and said supporting linkage and for guiding said copy receiving assembly within said casing, and a rope means connected at opposite points to the upper portion of said casing and frictionally engaging said rotatable members, supporting said copy receiving assembly with copy thereon in engagement with said platen member in its closed position, and permitting movement of said platen member to an open position without appreciable change in position of said copy supports.

7. A copy holder comprising a casing providing a pair of opposed guideways, a platen member mounted on the top of said casing, a parallelogram linkage having two pairs of opposite links, a pair of copy supports mounted respectively on each link of one pair of opposite links thereof, a pair of rods having their ends in said guideways and respectively each supporting each link of the other pair of opposite links, a pair of pulleys each adjacent the opposite ends of one of said rods, a rope member having its ends attached to said casing at points above the bottoms of said pulleys and intermediately encircling and supporting said pulleys, and an adjustable means connected to and varying the position of said rope member and said copy supports with respect to said casing.

8. A copy holder comprising a casing providing a pair of opposed guideways, a platen member mounted on the top of said casing, a parallelogram linkage having two pairs of opposite links, a pair of copy supports mounted respectively on each link of one pair of opposite links thereof, a pair of rods having their ends in said guideways and respectively each engaging each link of the other pair of opposite links, a pair of pulleys each adjacent opposite ends of one of said rods and attached to one of the links of said parallelogram linkage, a rope member supported at each end on said casing at opposite points above the bottoms of said pulleys and intermediately in frictional engagement with said pulleys to restrain relative movement of said copy supports, and an adjustable means connected to and varying the position of said rope

member and said copy supports with respect to said casing.

9. A copy holder comprising a casing having a pair of spaced parallel walls each provided with oppositely located guideways, a platen member mounted on the top of said casing, a pair of copy supports, two parallelogram linkages in spaced relation and each having the links of one set of opposite pairs attached respectively to said copy supports, a pair of transverse rods having their ends in engagement with said guideways and respectively extending through each link of the other set of opposite pairs, a pair of pulleys on one of said rods and each attached to corresponding links of said other set of opposite pairs of links, two lengths of rope attached at one end on said casing above the bottoms of said pulleys and intermediately encircling respective pulleys, a shaft rotatably mounted between said walls above the bottoms of said pulleys and carrying a pair of pulleys to which the other ends of the lengths of said rope are attached, and a manually operable means rotatably mounted on said casing for rotating said shaft.
10. A copy holder comprising a casing having a pair of spaced parallel walls each provided with oppositely located guideways, a platen member having a transparent panel mounted for movement to closed and open positions, a pair of copy supports, two parallelogram linkages in spaced relation and each having the links of one set of opposite pairs attached respectively to said copy supports, a pair of transverse rods having their ends in engagement with said guideways and respectively extending through each link of the other set of opposite pairs, a pair of pulleys mounted on one of said rods and each attached to corresponding links of said other set of opposite pairs of links, two lengths of rope attached at one end on said casing above the bottoms of said pulleys and intermediately encircling respective pulleys, a shaft rotatably mounted between said walls above the bottoms of said pulleys, carrying a worm wheel and carrying a pair of drums to which the other ends of the lengths of said rope are attached, and a manually operable means rotatably mounted on said casing and including a worm in engagement with said worm wheel and for rotating said drums and for moving said copy supports toward or away from the closed position of said platen member.
